UNITED STATES PATENT OFFICE.

LOUIS R. HORTON, OF PROVIDENCE, RHODE ISLAND, ASSIGNOR TO JOSEPH B. KNOWLES AND STEPHEN M. KNOWLES, BOTH OF SAME PLACE.

DESIGN FOR A HANDLE FOR SPOONS, &c.

SPECIFICATION forming part of Design No. 19,287, dated August 27, 1889.

Application filed August 5, 1889. Serial No. 319,838. Term of patent 7 years.

To all whom it may concern:

Be it known that I, LOUIS R. HORTON, a citizen of the United States, residing at Providence, in the county of Providence and State 5 of Rhode Island, have invented and produced a new and original Design for Handles, of which the following is a specification, reference being had to the accompanying drawings, forming part thereof.

Figure 1 is a front view of a spoon and the handle thereof. Fig. 2 is a view of the rear portion of the handle.

The leading feature of my design consists in a symmetrical wave-like outline, forming, with the gradually-increasing width, alternating enlargements and contractions in the width of the handle, spiral lines traced near the center of the alternate enlargements, and foliage traced around, between, above, and below the spirals.

A in the drawings designates the bowl of a spoon. It may, however, be the bowl of a ladle or the tine portion of a fork.

B indicates the handle. The narrow portion of the handle at c is curved outward on both sides of the handle in opposite directions to the point d, where it commences to

curve inward to e. Thence it again curves outward to d', thence inward to e', outward to d², and inward to e², the width of the handle increasing symmetrically from c to d². Around points in the center of the handle, near the enlargements d, d', and d², the spiral lines f surround a circular space. The foliage g is traced winding around, between, above, and below the spirals f. The back of the handle presents the symmetrical wave-line, gradually increasing the width of the handle, with a line parallel to the outline ending in foliage outlines at the contractions e, e', and e². 40

What I claim is—

The design for a handle herein shown and described, the same consisting in the symmetrical wave-like outline, forming, with the increasing width, alternating enlargements 45 and contractions in the width of the handle, spiral lines on the enlargements, and foliage around, between, above, and below the spirals, as set forth.

LOUIS R. HORTON.
